UNITED STATES PATENT OFFICE.

GEORGE M. HUBBARD, OF NEW HAVEN, CONNECTICUT, ASSIGNOR TO W.
& E. T. FITCH, OF SAME PLACE.

SNAP-HOOK.

SPECIFICATION forming part of Letters Patent No. 350,055, dated September 28, 1886.

Application filed July 12, 1886. Serial No. 207,732. (No model.)

To all whom it may concern:

Be it known that I, GEORGE M. HUBBARD, of New Haven, in the county of New Haven and State of Connecticut, have invented a new Improvement in Snap-Hooks; and I do hereby declare the following, when taken in connection with accompanying drawings and the letters of reference marked thereon, to be a full, clear, and exact description of the same, and 10 which said drawings constitute part of this specification, and represent, in—

Figure 1, a perspective view; Fig. 2, a top view complete; Fig. 3, a top view, the tongue removed, and showing the recess as cast sufficiently open for the introduction of the spring; Fig. 4, a perspective view of the tongue; Fig. 5, a longitudinal section of the hook complete; Fig. 6, a longitudinal section showing the method of introducing the tongue.

This invention relates to an improvement 20 in snap-hooks, and particularly to the snap known as the "Bristol" snap—that is to say, a snap in which the tongue is constructed with a recess in its hub to receive a torsion-spring, 25 and the tongue and spring hung in a recess in the body of the hook, and particularly to that class of such snaps in which the pivot upon which the tongue hinges is cast a part of the body, in contradistinction to first drilling the 30 body and introducing the wire for the pivot, and such, for illustration, as that patented to Charles B. Bristol March 30, 1880. In this construction of snaps it is necessary that the recess be cast open, so that the cheeks are sufficiently far apart to permit the tongue to pass 35 the pivot in entering the recess, and then the cheeks or sides are forced toward each other to bring them into the proper relation to the sides or hub of the tongue. In bending the 40 cheeks to thus embrace the tongue very many are broken, so many that the loss adds materially to the cost of manufacture. Attempts have been made to overcome this difficulty by bending some other portion of the hook—as, 45 for illustration, to bend the tongue around the pivot, or to form lugs upon the body, which are bent down over the tongue. Such bending, however, does not to any material extent reduce the breakage.

The object of my invention is to so greatly 50 reduce the extent of bending of the cheeks as

to practically avoid the liability of breakage; and the invention consists in the construction as hereinafter described, and particularly recited in the claim.

A represents the body of the snap, constructed with a hook, B, at one end and eye C at the opposite end, and with a recess, D, at the eye end of the body and opening into the eye. On one of the cheeks of this recess a stud, a, is cast as a part of the body, and extending transversely nearly across the recess, but so as to leave a space between the opposite cheek and the end of the pivot. On one or both sides of the recess at its rear end is an inwardly-projecting lug, b.

E is the tongue, of substantially the usual shape, the hub of the tongue somewhat less in thickness than the width of the recess D. The width of the tongue proper or at the hub is 70 somewhat less than the distance between the legs b b, and the hub of the tongue is constructed with a recess, d, in one side, as in the Bristol patent before referred to, this recess being adapted to receive the spring. Through the 75 hub is a concentric opening corresponding to the pivot, and which opening extends radially outward and downward, so as to open upon the under side of the hub and as seen in Fig. 5.

F is the spring, preferably a torsion-spring, 80 the diameter of the coil corresponding to the diameter of the recess in the hub of the tongue, the arms extending therefrom, and so that when in the position seen in Fig. 5 one arm will take a bearing beneath the tongue, and the other 85 arm will take a like bearing upon the body below, the tendency being to hold the end of the tongue against the nose of the hook, as in the Bristol snap.

In assembling the parts the spring is arranged upon the stud, the space between the end of the stud and the opposite cheek permitting such introduction. The tongue is then introduced by passing it up through the loop until the hub comes to a position below 95 the lugs b, as indicated in broken lines, Fig. 6, and in which position the opening in the side of the hub may be permitted to pass onto the pivot. The tongue is now turned forward and upward into the recess and inside the lugs, as 100 seen in Fig. 6. The opening in the side of the hub passes up over the stud, and the recess in

the hub sets over the spring. The tongue is then turned forward and under the nose of the hook, and the spring will yieldingly hold it in such position. The space between the two cheeks permits the tongue to be turned to one side sufficiently far to pass beneath the nose of the hook, so that the casting of the nose of the hook out of its natural plane, and bending it into that plane after the tongue is introduced, as in some manufacture, is avoided. The two cheeks are now forced toward each other to bring them close up to the sides of the hub of the tongue, as seen in Fig. 2, and so as to prevent the lateral displacement of the tongue.

While I prefer to cast a lug, *b*, upon each side of the recess, it will be understood that one may be omitted, as the remaining one will serve to prevent displacement of the hook after once properly set. By this construction the extent of bending the sides at the recess is so slight that a break rarely occurs.

I do not wish to be understood as claiming, broadly, a snap-hook in which the tongue is constructed with a hook-like hub to embrace the pivot, as such, I am aware, is not new.

I claim—

In a snap-hook, substantially such as described, the body constructed with a recess at its loop end to receive the hub of the tongue, 30 the said recess having a pivot cast upon one of the cheeks and extending transversely toward the other, but so as to leave a space between the end of the pivot and the opposite cheek, and also with one or more lugs, *b*, at the rear, 35 extending inward over said recess, combined with a tongue constructed with a hub adapted to enter said recess, and the tongue near the hub constructed thinner and so as to pass between the lugs into the recess, and the hub of 40 the tongue also constructed with a concentric recess upon one side, and with a pivot-opening in the opposite side, the said opening extending radially outward and downward, and a spring arranged on said pivot within the re- 45 cess, substantially as described.

GEORGE M. HUBBARD.
